(57) **CLAIM**

The ornamental design for an orthotic device, as shown and described.

DESCRIPTION

FIG. 1 is a perspective view of an orthotic device.

FIG. 2 is an end view of the orthotic device.

FIG. 3 is a front view of the orthotic device.

FIG. 4 is a rear view of the orthotic device; and,

FIG. 5 is a top view of the orthotic device.

The dash-dot broken lines in FIGS. 1 and 3-5 immediately adjacent to claimed surfaces represent the boundaries of the claimed design and also show portions of the orthotic device that form no part of the claimed design. The dash-dash broken lines in FIGS. 1-4 show portions of the orthotic device and form no part of the claimed design. None of the broken lines form any part of the claimed design.

(Continued)

The orthotic device is shown with a symbolic break in its length. The appearance of any portion of the article between the break lines forms no part of the claimed design.
